ROTATABLE SEAL FOR COWLINGS

Maurice E. Cushman, Verona, N. J., assignor to
 Curtiss-Wright Corporation, a corporation of
 Delaware

Application January 30, 1951, Serial No. 208,636

8 Claims. (Cl. 170—160.23)

1

This invention relates to spinners for aeronautical propellers and more particularly to a sealing arrangement for controllable pitch propeller blades where they pass through a propeller spinner. The invention, in part, comprises improvements over that described and claimed in Patent No. 2,522,083, issued September 12, 1950, to Leo Avondoglio.

Sheet metal spinners have been used for some time to surround a propeller hub and to embrace the propeller blades, so that airflow over the outside of the spinner is streamlined for minimum drag of the propeller. In modern high speed aircraft, this spinner streamlining becomes particularly important for drag reduction but the problem of adequately sealing the blades as they pass through the spinner becomes troublesome particularly where the propeller blades have considerable chord and where the spinner diameter is relatively small. For instance, if a spinner has a diameter of the order of 2 feet and the blades of a three-bladed propeller each have a chord of about 14 inches, the openings in the spinner through which the blades pass have large size relative to the spinner. If bumps on the spinner are used, with the blades starting beyond the profile of the spinner, increase in drag is immediately caused. If an arrangement such as in the Avondoglio patent above mentioned is used, the warping blade seal is difficult to control and retain due to the considerable curvature thereof resulting from the small spinner diameter.

This invention sets out to provide a warping blade seal for a small diameter spinner whose position and shape is at all times perfectly controlled to the end that the spinner seal conforms to the profile of the spinner and to the end that minimum drag is induced in the system.

It is an object of the present invention to provide an efficient, low drag, fully controlled spinner seal for the blades of a controllable pitch propeller. It is a further object of the invention to provide a propeller and hub construction of relatively small diameter, which includes provision for affording sealing of the blades as they pass through a rotating spinner associated with the propeller. A further and principal object of the invention is to provide reinforcing means for a rotatable spinner seal to support the seal against centrifugal force during propeller rotation. It is a further object of the invention to provide a multi-part spinner and streamlining for a propeller wherein a cen-

2

tral portion of the spinner is secured to and rotates with the propeller, said central portion being bordered by non-rotating forward and rearward parts. In this connection, the non-rotating forward part of the spinner, which includes a pointed end for air entry disposed a considerable distance in advance of the propeller hub, is free from centrifugal effects and thereby has no tendency to upset the balance of the propeller system. Furthermore, with a non-rotating spinner entry, the non-rotating portion may contain various sorts of auxiliary apparatus which add to the utility of the aircraft on which the installation is made.

Further objects of the invention will become apparent in reading the annexed detailed description in connection with the drawings which exemplify a preferred arrangement of the spinner and associated parts. The drawings and description are not to be considered as limiting the scope of the invention, the specific improvements which comprise the invention being set forth in the appended claims.

In the drawings, in which similar reference characters indicate similar parts,

Fig. 1 is a fragmentary longitudinal view, partly in section, through an aircraft propeller and spinner showing the provisions of the invention.

Figs. 2 and 3 are fragmentary elevations of the propeller and spinner assembly, showing one of the propeller blades in different positions of pitch;

Fig. 4 is a fragmentary longitudinal section through a portion of the propeller showing details of construction thereof; and

Fig. 5 is a frontal view, partly in section, of the spinner and propeller hub, also showing certain details of construction of the invention.

In the figures, a propeller shaft is indicated at 10, the shaft extending forwardly from a nose structure 11 of the aircraft. Upon the shaft 10 a propeller hub 12 is mounted through splines 13 and conventional securing means 14, the propeller hub including blade sockets, one of which is shown at 15. Upon a rearward extension 16 of the propeller hub, a pitch changing mechanism 17 is mounted, the mechanism 17 being piloted on the propeller hub so that the hub may rotate relative thereto. The mechanism is secured against rotation to the structure 11 by suitable dowel arrangements 18. The mechanism 17 may be provided at its rim with lugs 19 to which braces 20 are secured as at 21, the braces 20 providing a forward mounting and

anchorage for a rearward stationary cowling 22.

Embracing the propeller hub 12 is a rotating spinner cowling 23, attached to the propeller hub 12 by a forward diaphragm 24 and a rearward diaphragm 25, the two diaphragms being secured to the front and rear portions of the propeller hub as by screws 26 and 27. The spinner 23 may be made in several segments, as shown in Fig. 5, these segments being secured to each other at flanges 29, whereby spinner construction may be accomplished by the use of stampings rather than by the use of a spun conical member. The spinner 23 is conical in form, at least in its central portion, and circular openings are provided therearound through which propeller blades 31 project, the openings having a diameter somewhat greater than the chord of the blades. The blades 31 in the embodiment shown are substantially rectangular in planform in their airfoil portions and these airfoil portions extend within the spinner 23 and terminate in a circular shank portion 32 secured within the hub socket 15. A transition from the airfoil portion 31 of the blade to the cylindrical portion 32 thereof is accomplished by a blending shank portion 33 shown in Fig. 5. The inner end of the shank 32 is provided with a flange 34 engaged by an inner bearing race 35 engaged in turn by bearing balls 36 engaged in turn with a bearing retaining nut 37 screwed within each hub socket 15. By this arrangement, each propeller blade is secured within its hub socket and is capable of rotation about the blade axis for pitch change. Pitch change is imparted to the propeller blades through the engagement of a hub-carried worm 39 engaging a worm wheel 40 secured to each blade flange 34. Driving connections to the worms 39 are effected from the pitch change mechanism 17, these connections not being shown since they have been adequately disclosed in the prior art and do not comprise a portion of the invention. A pitch changing arrangement for a propeller of this type is exemplified by Mergen et al. patent application S. N. 143,636, filed February 11, 1950.

As previously indicated, the spinner 23 is provided with substantially circular openings, designated at 42, through which the propeller blades 31 pass. These openings are circular when the spinner cowl 23 is flat; when the spinner cowl 23 is curved to conical form, the openings 42 depart in their projected form from a true circle, but remain effective as circles on the surface of the spinner cowl. As will be noted by the proportions of the drawings, these openings are rather large and if they are not sealed in some manner, the smooth continuity of airflow over the exterior of the spinner would be seriously interfered with. These openings need to be substantially circular since the propeller blades have a pitch change range of approximately 120 degrees from a feathering position as shown in Figs. 1 and 3-5, to a negative pitch angle of about 20 degrees. The border of each opening 42 is constructed with a track comprised by the spinner material at the edge of the opening as at 43, and an annular element 44 underlying the edge 43 in spaced relation and secured as at 45 to the spinner 23.

A flexible circular seal disk 46 is provided with a slot 47 having clearance relation with the propeller blade 31 and embracing the blade. A seal gasket 48, fitted to the disk, cushions and seals the joint between the blade 31 and the sealing disk 46. The disk 46 is elastically curved to a

conic configuration to conform to the profile of the spinner 23, the edges of the disk 46 being engaged in the track formed by the elements 43 and 44. As the propeller blade is rotated for pitch change, the disk 46 rotates therewith but because of the flexibility of the disk, it may curve along different diameters thereof as the disk is rotated so that the outer surface of the disk at all times conforms to the general conic shape of the spinner. The several views of the drawings are believed to show this arrangement, Figs. 2 and 3 particularly indicating two pitch positions of the propeller blades while the spinner seal 46 remains in the curvature of the spinner 23. The 15 shaded lines in these two figures may be considered to represent surface elements of the conic section of the spinner and of the spinner seal disk 46, these surface elements remaining the same regardless of the pitch position of the propeller blades and of the degree of turning of the spinner seal disk 46 in the spinner.

With the propeller rotating at high speed, the seal disks 46 are disposed in a high centrifugal field which, if not compensated, would tend to 25 buckle the disks and to fling them outwardly so that they might either be thrown from the propeller or might buckle to the point where they would jam in the spinner tracks and not be capable of free rotation with the blades as the blades change in pitch. To reinforce the spinner disks 46 against the effects of centrifugal force, a plurality of struts 50 are secured to the disk as shown in Figs. 1 and 5, there being a total of 8 struts for each disk in the arrangement shown. Inner struts 51 are pivoted to the struts 50 at 52, the struts 51 at their inner ends carrying yokes 53 engaging around a cam track 54 formed on an inner tapered bore on the blade retaining nut 37 screwed into the blade socket 15. The cam track 54 is of annular waved form as indicated in Fig. 4, the rise and fall of the cam parallel to the blade axis being a function of the rise and fall of the edge of the opening 42 in the spinner parallel to the blade axis. The several struts 50, 51, accordingly, secure the disk 46 in a conic configuration the same as the conic configuration of the spinner 23. The yokes 53 carry rollers 55 engaging the underside of the cam track 54 so that, when the propeller is rotating, the struts and yokes may travel freely around the cam track as the propeller blade is changed in pitch. The yokes 53 are driven with the propeller blade during pitch change of the latter so that the yokes will at all times engage the proper portion of the cam track to hold the spinner disk in its correct position, and also to drive the spinner disk 46 with the blade when blade pitch is changed. This drive avoids direct driving of the disk by the blade through the gasket seal 48, avoiding possible buckling of the seal disk. To this end, the shank 33 of the blade is provided with lugs 57 to which spiders 58 are secured. The spiders are provided with grooves 59 within each of which a yoke 53 is engaged. To stabilize the driving of the disk, each strut 51 is provided with an extension 56, slidably engaging a corresponding groove 59 in the spider 58. Thus, as the blade turns for pitch change, the yokes 53 and extensions 56 are constrained to turn therewith, sliding up and down the grooves 59 in accordance with the configuration of the waved cam 54, and driving the disk 46 through the struts 50 and 51. Part of the centrifugal load on the disk 46 is carried by the struts 50, 51 while part of it is also carried where the edge of the disk 46 engages the

track elements 43 and 44. At the disk edge, low friction gaskets, preferably of phenolic composition, are secured on either side of the edge of the disk 46 so that as the disk turns in the track, undue resistance will not be encountered as a result of the centrifugal force acting on the disk.

As will be noted in the figures, the inner ends of the edges of the airfoil portions of the propeller blades are curved as at 60 to accommodate the relative radial motion of the disk 46 to the blade 31 as the blade is turned for pitch change. This arrangement enables the presentation of airfoil sections of the propeller blade on the outer surfaces of the cowling at all times, to minimize the drag in the system.

In the form of spinner and propeller systems contemplated in this application, the nose portion of the spinner has a high fineness ratio, the nose portion of the spinner extending outwardly beyond the propeller a substantial distance to minimize drag in the system. To avoid balancing problems on a long slender spinner of this sort, the arrangements of this invention allow the forward portion of the spinner to be mounted non-rotationally. To this end, a non-rotating sleeve 62, secured within the structure 11, passes through the propeller shaft 10, the shaft rotating around the sleeve. The forward end of the sleeve 62 is piloted with respect to the propeller through a bearing 63. Brackets 64, secured to a fitting 65 at the forward end of the sleeve, support the non-rotating forward cowling 66 through fittings 67. In view of the hollow nature of the forward stationary cowling 66 and of the sleeve 62, various sorts of equipment such as instruments and the like may be incorporated in the forward cowling.

Various modifications may be made in the invention while still coming within the scope thereof. For instance, the cam track 54 and associated elements of the system need not necessarily be a portion of the propeller hub and blade retaining nut, but rather, such cam track could be secured to the propeller hub as a separate assembly. The number of struts 50, 51 with their associated elements may be increased or decreased to provide adequate support for the spinner disk 46 in accordance with the weight and dimensions of the part to be supported. The spider arrangement 58 is susceptible to considerable change and modification as the proportions and character of the propeller blade used in connection with the invention might vary. Suitable reinforcement may be provided in the seal disk 46 at those portions thereof adjacent the leading and trailing edges of the propeller blades where the material does not have as much body as in other portions of the spinner disk where greater surface area of material exists. Also, the spinner disk can be completely supported by the cam and strut arrangements above described without recourse to auxiliary support of the spinner disk edges by the rotating spinner.

Though but a single embodiment illustrating the invention has been illustrated and described, it is to be understood that the invention may be applied in various forms. Changes may be made in the arrangements shown without departing from the spirit or scope of the invention as will be apparent to those skilled in the art and reference should be made to the appended claims for a definition of the limits of the invention.

What is claimed is:

1. In an aeronautical propeller and cowling arrangement, said propeller having blades extending through said cowling for pitch change, a

substantially circular track in the cowling around each blade, a warpable substantially circular closure member embracing each blade in clearance relation and movable with said blades and fitted to said track, the latter lying in a conic surface and said closure member conforming to said conic surface in all pitch positions of the associated blade, a waved substantially annular cam concentric with the blade and secured to said propeller, said cam being waved substantially in conformance with the profile of said track, a plurality of struts engaging said cam and secured to the inner surface of said closure member, and means on the propeller blade engaging said struts to drive said struts about the blade axis as the blade changes in pitch.

2. In a rotating cowling for an aeronautical propeller comprising a controllable pitch blade, a conic surface portion of said cowling adjacent said blade having a circular opening through which said blade passes, a closure disk embracing the blade in clearance relation and movable with the blade during pitch change, said disk being warpable to the profile of said conic surface, a waved cam secured to said propeller within said cowling, a plurality of cam followers spaced around and engaging said cam, means securing said cam followers to said disk, and means to drive said means and disk rotationally about the blade axis as said blade is changed in pitch.

3. In a rotating cowling for an aeronautical propeller comprising a controllable pitch blade, a conic surface portion of said cowling adjacent said blade having a circular opening through which said blade passes, a closure disk embracing the blade in clearance relation and movable with the blade during pitch change, said disk being warpable to the profile of said conic surface, a waved cam secured to said propeller within said cowling, a plurality of cam followers spaced around and engaging said cam, means securing said cam followers to said disk, means to drive said means and disk rotationally about the blade axis as said blade is changed in pitch and track means secured to the cowling edge bordering said circular opening, the closure disk edge being engaged in said track means.

4. In a rotating cowling embracing a propeller, said cowling having a conic surface, said cowling having a substantially circular opening through which a blade of the propeller projects, said propeller including a hub and a blade socket, a waved cam secured to said socket having a wave configuration like the configuration of the edge of the cowling opening, a plurality of cam followers movable around and engaging said cam, a strut secured to each cam follower, and a warpable closure disk embracing the propeller blade to the inner surface of which said struts are articulately secured in spaced relation.

5. In a rotating cowling embracing a propeller, said cowling having a conic surface, said cowling having a substantially circular opening through which a blade of the propeller projects, said propeller including a hub and a blade socket, a waved cam secured to said socket having a wave configuration like the configuration of the edge of the cowling opening, a plurality of cam followers movable around and engaging said cam, a strut secured to each cam follower, a warpable closure disk embracing the propeller blade to the inner surface of which said struts are articulately secured in spaced relation, and means for driving said cam followers around said

track with the propeller blade as it changes in pitch.

6. In a rotating cowling embracing a propeller, said cowling having a conic surface, said cowling having a substantially circular opening through which a blade of the propeller projects, said propeller including a hub and a blade socket, a waved cam secured to said socket having a wave configuration like the configuration of the edge of the cowling opening, a plurality of cam followers movable around and engaging said cam, a strut secured to each cam follower, a warpable closure disk embracing the propeller blade to the inner surface of which said struts are articulately secured in spaced relation, and means providing interengagement between the edge of said disk with the cowling edge at said opening.

7. In a controllable pitch propeller system comprising a hub and sockets, and blades rotatably secured in said sockets for pitch change, a blade retaining nut screwed into each socket and embracing the associated blade, said nut having clearance around said blade and having a waved cam track formed thereon, a warpable disc surrounding the blade outwardly of said hub socket, a plurality of cam followers spaced around said cam track, and a plurality of means securing said warpable disk to said cam followers.

8. A propeller system including a hub having

controllable pitch blades extending therefrom, a spinner secured to and rotatable with said hub, a curved guide carried by the hub within said spinner, a streamlined air entry cowl in advance of and blended into the form of said spinner, means mounting said air entry cowl against rotation with the propeller, said spinner portion having openings through which the blades of the propeller project, flexible means movable with the propeller blades as they turn for pitch change to seal the blades to the surface of said spinner, and mechanism articulately connecting said curved guide with said flexible means to conform the shape of said flexible means, at all times, to the shape of said spinner.
